DESIGN FOR A MOCK MACHINE GUN ATTACHMENT FOR BICYCLES

Charles W. Redlund, West Hartford, Conn.

Application July 18, 1942, Serial No. 107,593

Term of patent 7 years

To all whom it may concern:

Be it known that I, Charles W. Redlund, a citizen of the United States, residing at West Hartford, in the county of Hartford and State of Connecticut, have invented a new, original, and ornamental Design for a Mock Machine Gun Attachment for Bicycles, of which the following is a specification, reference being had to the accompanying drawing, forming a part thereof.

In the drawing:

Fig. 1 is a side elevational view of a mock machine gun attachment for bicycles showing my new design; and

Fig. 2 is a front elevational view thereof.

I claim:

The ornamental design for a mock machine gun attachment for bicycles, as shown.

CHARLES W. REDLUND.
